DESIGN FOR A TOP FOR A DISPENSING REFRIGERATOR

Robert E. Baker, Muncie, Ind., assignor to Glas-
cock Brothers Mfg. Co., Muncie, Ind., a corpo-
ration of Indiana

Application November 15, 1935, Serial No 59,596

Term of patent 14 years

To all whom it may concern:

Be it known that I, Robert E. Baker, a citizen of the United States, residing at Muncie, in the county of Delaware and State of Indiana, have invented a new, original, and ornamental Design for a Top for a Dispensing Refrigerator, of which the following is a specification, reference being had to the accompanying drawing, forming part thereof.

The figure is a perspective view of a top for a dispensing refrigerator embodying my design.

I claim:

The ornamental design for a top for a dispensing refrigerator, as shown.

In witness whereof, I have hereunto set my hand at Muncie, Indiana, this 8th day of November, A. D. one thousand nine hundred and thirty-five.

ROBERT E. BAKER,
